US00D862863S

(12) **United States Design Patent** (10) **Patent No.:** **US D862,863 S**
Buck (45) **Date of Patent:** **** Oct. 15, 2019**

(54) **INSOLE**(71) Applicant: **PROTALUS LLC**, West Linn, OR (US)(72) Inventor: **Christopher Buck**, West Linn, OR (US)(73) Assignee: **PROTALUS LLC**, West Linn, OR (US)(***) Term: **15 Years**(21) Appl. No.: **29/653,413**(22) Filed: **Jun. 14, 2018****Related U.S. Application Data**

(63) Continuation of application No. 29/586,543, filed on Dec. 5, 2016, now Pat. No. Des. 820,573.

(51) **LOC (12) Cl.** ..... **02-04**(52) **U.S. Cl.**USPC ..... **D2/961**(58) **Field of Classification Search**USPC D2/896, 946, 947, 951, 953, 959, 960, D2/961, 969

CLAIM

The ornamental design for an insole, as shown and described.

DESCRIPTION

FIG. 1 is a perspective view of an insole of my new design; FIG. 2 is another perspective view thereof;

FIG. 3 is a top plan view thereof;

FIG. 4 is a bottom plan view thereof;

FIG. 5 is a first side elevation view thereof;

FIG. 6 is an opposing second side elevation view thereof;

FIG. 7 is a front elevation view thereof; and,

FIG. 8 is a rear elevation view thereof.

The broken lines in the figures illustrate environmental structure only and form no part of the claimed design.
